UNITED STATES PATENT OFFICE

CHRISTOPHER Y. WEMPLE, OF NEW YORK, N. Y.

DESIGN FOR AN APRON.

Specification forming part of Design No. **11,265**, dated June 24, 1879; application filed May 1, 1879.
[Term of patent 14 years.]

To all whom it may concern:

Be it known that I, CHRISTOPHER Y. WEMPLE, of the city of New York, in the county of New York and State of New York, have invented a new and original Design for an Apron; and I do hereby declare that the following is a full, clear, and exact description thereof, reference being had to the accompanying drawing, and to letters of reference marked thereon, which form a part of this specification.

The drawing represents a front view of the apron.

The invention has for its object the production of a new and original design for an apron; and consists in making the body of the apron in the form of a Norman shield, with a part of another and smaller shield superimposed for a flap, and pockets of still smaller shields, and the ornamentation of the apron so formed with stars and stripes.

A represents the body of the apron, made in the form of a Norman shield, and ornamented with the stars and stripes. B is the flap, an extension of the body A, forming a part of another shield, which may be ornamented with the stars and stripes; or it may have the American eagle in the center, with a border of stars, as shown. The small shields forming the pockets are also appropriately ornamented.

I claim as my invention—

1. The design for an apron, consisting of the body in the form of a shield ornamented with the stars and stripes, and the flap orna-

mented with the American eagle perched on the central point of the shield, which forms the body, substantially as described, and shown in the accompanying illustration.

2. The design for an apron having body, flap, and pockets, consisting of the body and pockets, respectively, in the form of Norman shields, with a flap of essentially the same shape, substantially as described, and shown in the accompanying illustration.

3. The design for an apron, consisting of the body in the form of a Norman shield, with a border of blue dotted with white stars, and the center of the shield ornamented with perpendicular alternate stripes of red and white, substantially as described, and shown in the accompanying illustration.

4. The design for an apron, consisting of the body in the form of a Norman shield, with a border of blue dotted with white stars, having the center ornamented with perpendicular alternate stripes of red and white, a flap of similar shape, with like border, the face ornamented with an eagle, and pockets of similar shape, with a narrow blue border, each ornamented with a star or stars, all substantially as described, and for the purpose set forth.

In testimony that I claim the foregoing as my own I affix my signature in presence of two witnesses.

CHRISTOPHER Y. WEMPLE.
